UNITED STATES PATENT OFFICE.

OSKAR LASCHE, OF CHARLOTTENBURG, GERMANY, ASSIGNOR TO GENERAL ELECTRIC COMPANY, A CORPORATION OF NEW YORK.

INTERNAL-COMBUSTION ENGINE.

1,207,571.

Specification of Letters Patent.

Patented Dec. 5, 1916.

Application filed July 8, 1914. Serial No. 849,686.

To all whom it may concern:

Be it known that I, OSKAR LASCHE, a subject of the Emperor of Germany, residing at Charlottenburg, Germany, have invented 5 certain new and useful Improvements in Internal-Combustion Engines, of which the following is a specification.

The present invention relates to internal combustion engines of the type having two 10 oppositely moving pistons which serve to cover and uncover the inlet or scavenging exhaust ports, and in which the cranks of the respective pistons are angularly displaced relative to each other by an amount 15 somewhat less than 180 degrees so that the piston which controls the exhaust ports leads the other. As is known, the advantage of this arrangement is that the exhaust ports are opened prior to the opening of the inlet 20 ports so as to permit a portion of the exhaust gases to escape and the pressure in the cylinder to decrease before the inlet ports are uncovered, and are closed prior to the closing of the inlet ports so as to increase 25 the charge.

An engine of this type is designed to operate in one direction only, it being obvious that if reversed the piston controlling the inlet ports would then lead that controlling the 30 exhaust ports which would result in the inlet ports opening prior to the exhaust ports so that exhaust gases would escape through the inlet ports and mix with the incoming charge of air. This is due to the fact that 35 the pressure in the cylinder at this time would be greater than that of the scavenging air.

The object of the present invention is to provide an arrangement whereby an engine 40 of this type may be reversed.

For a consideration of what I believe to be novel and my invention, attention is directed to the following specification and the claims appended thereto.

45 Referring to the drawing, the figure is a longitudinal section of an internal combustion engine illustrating one form which my invention may take.

In the drawing, 3 indicates the cylinder

and 4, 5 the oppositely moving pistons which 50 control the inlet or scavenging ports 6 and the exhaust ports 7.

8 indicates a receiver or conduit through which the scavenging air is led to the inlet ports. This air is supplied under pressure 55 as is well understood. The exhaust gases are conveyed away by conduit 9. The pistons are connected to their respective cranks 10 and 11 by the connecting rods 12 and 13. The cranks 10 and 11 are angularly displaced relative to each other, as shown, whereby in forward operation, which in the present instance is clockwise, the piston 5 leads the piston 4 for the reasons already referred to.

65 Located in the inlet conduit 8 and controlling the passage of the supply of air therefrom to the admission ports 6 is a valve 14 yieldingly held on its seat by the spring 15. The stem 16 of the valve is connected to one 70 end of the hand lever 17 fulcrumed at 18, and by means of which the valve may be moved from its seat and held open. The valve 14 is also arranged to be opened by the toggle levers 19 and 20 attached at one end 75 to the valve stem and pivoted at the other end to the fixed support 21. This toggle is operated by the cam 22 mounted on a suitable shaft. As here shown the cam is mounted on the main shaft. It will be clear 80 that when the hand lever 17 is shifted to open valve 14 the toggle will be moved out of operative relation to the cam, while when moved to close the valve the toggle will be engaged by the cam to open the valve upon 85 each revolution.

At 23 and 24 are shown suitable openings through which fuel and starting air may be introduced, the fuel injector and air starting valve being omitted since they form no part 90 of the present invention.

During normal forward operation the hand lever 17 will be moved to the dotted line position and fastened in any suitable manner. This opens the valve 14 and moves 95 the toggle out of operative relation to the operating cam 22. The engine will then operate in the forward direction in the ordi-

nary manner. When it is desired to reverse the engine, the lever 17 is moved to the full line position. The valve will then be held to its seat by the spring 15 and the toggle will be moved into position to be engaged by the cam 22. The valve when closed cuts off the supply of air to the inlet ports and the cam will be so timed as to not open the same until the exhaust ports have been uncovered by the piston 5. By this means the supply of air on each cycle is cut off until the exhaust ports have been uncovered sufficiently to permit the pressure in the cylinder to decrease until it is substantially equal to or below that of the scavenging air.

In accordance with the provisions of the patent statutes, I have described the principle of operation of my invention, together with the apparatus which I now consider to represent the best embodiment thereof; but I desire to have it understood that the apparatus shown is only illustrative and that the invention can be carried out by other means.

25 What I claim as new and desire to secure by Letters Patent of the United States, is:

1. In an internal combustion engine, the combination of a cylinder, oppositely moving pistons therein, inlet and exhaust ports which are covered and uncovered by the pistons, cranks for the pistons which are angularly displaced relative to each other by an angle other than 180° whereby upon forward operation the piston controlling the exhaust ports leads the piston controlling the inlet ports, valve means for shutting off the supply of air to the inlet ports until the exhaust ports are uncovered when the engine is reversed.

40 2. In an internal combustion engine, the combination of a cylinder, oppositely moving pistons therein, inlet and exhaust ports which are covered and uncovered by the pistons, cranks for the pistons which are angularly displaced relative to each other by an angle other than 180° whereby upon forward operation the piston controlling the exhaust ports leads the piston controlling the inlet ports, valve means controlling the supply of air to the inlet ports, and means for holding said valve closed until after the exhaust ports begin to be uncovered when the engine is reversed.

55 3. In an internal combustion engine, the combination of a cylinder, oppositely moving pistons therein, inlet and exhaust ports which are covered and uncovered by the pistons, cranks for the pistons which are angularly displaced relative to each other by an angle other than 180° whereby upon forward operation the piston controlling the exhaust ports leads the piston controlling the inlet ports, and means for shutting off the supply of air to the inlet ports during

the period between the time when the inlet ports begin to open and the time when the exhaust ports begin to open when the engine is reversed.

4. In an internal combustion engine, the combination of a cylinder, oppositely moving pistons therein, inlet and exhaust ports which are covered and uncovered by the pistons, cranks for the pistons which are angularly displaced relative to each other by an angle other than 180° whereby upon forward operation the piston controlling the exhaust ports leads the piston controlling the inlet ports, valve means for shutting off the supply of air to the inlet ports until after the exhaust ports begin to uncover, a lever through which said valve means is operated, a cam, and means for moving the lever into and out of operative relation to the cam.

5. In an internal combustion engine, the combination of a cylinder, oppositely moving pistons therein, inlet and exhaust ports which are covered and uncovered by the pistons, cranks for the pistons which are angularly displaced relative to each other by an angle other than 180° whereby upon forward operation the piston controlling the exhaust ports leads the piston controlling the inlet ports, valve means for shutting off the supply of air to the inlet ports until after the exhaust ports begin to uncover, a lever through which said valve means is operated, a cam, and means for simultaneously moving the valve to closed position and the lever into operative relation to the cam.

6. In an internal combustion engine, the combination of a cylinder structure having a combustion space, two pistons therein which move in unison toward and away from said combustion space, a single set of inlet and exhaust ports which are covered and uncovered by the pistons, cranks for the pistons which are angularly displaced relative to each other by an angle other than 180° whereby upon forward operation the piston controlling the exhaust ports leads the piston controlling the inlet port, and means for shutting off the supply of air to the inlet port until the exhaust port is uncovered when the engine is reversed.

7. In an internal combustion engine, the combination of a cylinder structure having a combustion space, two pistons therein which move in unison toward and away from said combustion space, inlet and exhaust ports which are covered and uncovered by the pistons, cranks for the pistons which are angularly displaced relative to each other by an angle other than 180° whereby upon forward operation the piston controlling the exhaust port leads the piston controlling the inlet port, valve means

for shutting off the supply of air to the inlet port until after the exhaust port begins to uncover, a lever through which said valve means is operated, a cam, and means for moving the lever into and out of operative relation to the cam.

In witness whereof, I have hereunto set my hand this 20th day of June, 1914.

OSKAR LASCHE.
